UNITED STATES PATENT OFFICE.

JOHN C. HUNTER, OF CINCINNATI, OHIO, ASSIGNOR TO JACOB MEERSE, OF CINCINNATI, OHIO.

DESIGN FOR A DISPLAY STAND.

Application filed October 3, 1922. Serial No. 3,872. Term of patent 14 years.

To all whom it may concern:

Be it known that I, JOHN C. HUNTER, a citizen of the United States, residing at Cincinnati, in the county of Hamilton and State of Ohio, have invented a new, original, and ornamental Design for a Display Stand, of which the following is a specification, reference being had to the accompanying drawing, forming part thereof, in which the figure shows a perspective view of my new, original, and ornamental design.

I claim:

The ornamental design for a display stand, substantially as shown.

JOHN C. HUNTER.

Witnesses:

CLARA HECKMANN,
JOSEPH LEMKUHL.
